(**) Term: **15 Years**

(21) Appl. No.: **35/508,770**

(57) **CLAIM**

(22) Filed: **Apr. 18, 2019**

The ornamental design for an electrocardiograph for a wireless communication device, as shown and described.

(80) **Hague Agreement Data**

Int. Filing Date: **Apr. 18, 2019**

DESCRIPTION

Int. Reg. No.: **DM/206203**

Int. Reg. Date: **Apr. 18, 2019**

Fig. 1.1 is a perspective view of the electrocardiograph for a wireless communication device showing our new design;

Int. Reg. Pub. Date: **Mar. 6, 2020**

Fig. 1.2 is a front view thereof;

(51) **LOC (13) Cl.** **24-02**

Fig. 1.3 is a rear view thereof;

(52) **U.S. Cl.**

Fig. 1.4 is a left side view thereof;

USPC **D24/167**

Fig. 1.5 is a right side view thereof;

(58) **Field of Classification Search**

Fig. 1.6 is a top view thereof;

USPC D24/186, 187, 167, 168, 200

Fig. 1.7 is a bottom view thereof; and

CPC . A61B 5/0006; A61B 5/04012; A61B 5/0456;

Fig. 1.8 is another perspective view.

A61B 5/04085; A61B 5/0452; A61B

5/044

The broken lines show unclaimed portions of the electrocardiograph for a wireless communication device and form no part of the claimed design. The dot dash broken lines in the figures show boundaries that form no part of the claimed design.

See application file for complete search history.
